UNITED STATES PATENT OFFICE

ADELMER M. BATES, OF CHICAGO, ILLINOIS, ASSIGNEE TO BATES VALVE BAG COMPANY,
OF CHICAGO, ILLINOIS, A CORPORATION OF WEST VIRGINIA.

WIRE TIE FOR TWISTING BAGS.

1,168,781.

Specification of Letters Patent. Patented Jan. 18, 1916.

Application filed September 8, 1913. Serial No. 738,517.

To all whom it may concern:

Be it known that I, ADELMER M. BATES, a citizen of the United States, residing at Chicago, in the county of Cook and State of Illinois, have invented a certain new and useful Improvement in Wire Ties for Twisting Bags, of which the following is a specification.

My invention is illustrated in one form in the accompanying drawings.

Figure 1 is a view of two sectional wires. Fig. 2 is a view of the same after the two loops have been formed. Fig. 3 is a view of the same with the twisted ends of the two wires bent toward the axis of the bag encircling the loop. Fig. 4 is a view of the tie, with the key loop bent up perpendicular to the holding loop. Fig. 5 is a view of the tie with the ends of the wires adjacent to the key loop upset. Fig. 6 is a side elevation of the bag with the tie attached, partly broken away to show the tie in position.

Like letters refer to like parts throughout the several figures.

25 A and B are sections of wire, C shows their twisted ends adjacent to the bag encircling loop D.

E is a twisted portion of the two wires.

F is a key loop formed by twisting the 30 ends of the two sections together at G, or by upsetting them at H.

J is a bag having the gathered end K.

My invention relates to wire ties for bags, and particularly to ties intended to be used 35 on and formed in connection with empty bags, although, of course, this is not the only manner in which the invention could be used.

Each tie is composed of two separate sections of wire. Their two ends are joined and twisted and they are preferably turned inwardly and in this shape applied to the bag. The inwardly turned, twisted and untied ends are forced into the fabric or between the folds of the gathered end of the bag to be tied. Of course, the tie could be made and applied in a somewhat similar manner apart from the bag, but I am describing the convenient and practical method 45 of applying my invention. When the incomplete tie is in this position, the two pieces of wire are brought together and twisted preferably in such manner as to form a key loop, whereby the tie can be untwisted and 50 the bag loop be opened to untie the bag.

The two ends of the wire sections adjacent to the key loop are preferably bent inwardly so as to lie within such key loop and practically in the same plane therewith so that such severed ends are protected and provided with a guard to prevent their injuring objects in contact with which they might otherwise come. These ends can be upset. The important point is that they should be brought into a safety condition. The key loop with such ends in such position is now bent up into the folds of the gathered end of the bag. Thus I have a complete tie composed of two separate sections of wire, one pair of their severed ends being embedded in the fold or fabric of the bag, and the other pair of their ends being brought into a condition of safety and inclosed within or parallel with the folds of the gathered end of the bag. Of course, in actual practice and in the manufacture and application of such ties, there are the advantages that the wires may be supplied from the reel, that there are no loose bits or particles or separately manufactured rings, and that ties of varying sizes to suit the requirements of each particular bag in a series of irregular bags may be made with the least possible work.

With regard to the tie itself which is the subject matter of this application, the same consists of two separated and separate wire sections of practically the same length with their ends twisted together and one of them preferably bent and indented in the fabric of the bag, and the other developed into an untying or safety key which lies parallel with the gathered end of the bag.

I claim:

1. A wire tie for bags comprising two separate sections of wire with their ends twisted together, one pair of said ends twisted so as to form a key loop, and the other twisted ends projected inwardly toward the center of the tie.

2. A wire tie for bags comprising two separate sections of wire with their ends twisted together, one pair of said ends twisted so as to form a key loop with the twisted ends brought into a condition of safety, and the other twisted ends projected inwardly toward the center of the tie.

3. A wire tie for bags comprising two separate sections of wire with their ends twisted together, one pair of said ends twist-

ed so as to form a key loop with the twisted ends bent inwardly toward the center of such key loop and the other twisted ends projected inwardly toward the center of the tie.

4. A wire tie for bags comprising two separate wire sections twisted together to form a loop and separated twisted portions.

5. A wire tie for bags comprising two separate wire sections twisted together to form a loop and separated twisted portions, one of said twisted portions extending inwardly into the loop.

6. A wire tie for bags comprising two separate wire sections twisted together to form a loop and separated twisted portions, one of said twisted portions extending inwardly into the loop and a key loop formed in one of said twisted portions.

20 7. A wire tie for bags comprising two separate wire sections twisted together to form a loop and separated twisted portions, one of said twisted portions extending inwardly into the loop and a key loop formed 25 in one of said twisted portions, another

twisted portion being bent inwardly into the loop.

8. A wire tie for bags comprising two separate wire sections twisted together to form a loop and separated twisted portions, 30 one of said twisted portions having intermediate its ends a key loop the extreme end of the twisted portion being bent inwardly toward the center of the key loop.

9. A wire tie for bags comprising two 35 separate wire sections twisted together to form a loop and separated twisted portions, one of said twisted portions having intermediate its ends a key loop the extreme end of the twisted portion being bent inwardly toward the center of the key loop, the end of 40 the other twisted loop being bent inwardly toward the center of the bag engaging loop.

In testimony whereof, I affix my signature in the presence of two witnesses this 3d day 45 of September, 1913.

ADELMER M. BATES.
